Primary Examiner — Susan Moon Lee(74) *Attorney, Agent, or Firm* — True Shepherd LLC;
Andrew C. Cheng(57) **CLAIM**

The ornamental design for pet feeding bowl, as shown and described.

DESCRIPTION

FIG. 1 is a perspective view of a pet feeding bowl showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view thereof showing two bowls separated from a base for mounting the bowls.

The broken lines depict unclaimed subject matter for illustrative purposes only and form no part of the design claim.
